CLAIM

The ornamental design for the shaped levers, as shown and described.

DESCRIPTION

FIG. 1 is a perspective view of a first embodiment of the shaped levers showing the chair in phantom lines.

FIG. 2 is a perspective view of the shaped levers shown in FIG. 1 taken from a point above said shaped levers.

FIG. 3 is a perspective view of the shaped levers shown in FIG. 1 taken from a view below said shaped levers.

FIG. 4 is a side elevational view taken from the right of FIG. 2.

FIG. 5 is a front end elevational view of FIG. 2.

FIG. 6 is a side elevational view taken from the left of FIG. 2.

FIG. 7 is a rear end elevational view of FIG. 2.

FIG. 8 is a top plan view of FIG. 2.

FIG. 9 is a bottom plan view of FIG. 2.

FIG. 10 is a perspective view of a second embodiment of the design.

FIG. 11 is a perspective view of a third embodiment of the design.

FIG. 12 is a perspective view of a fourth embodiment of the design.

FIG. 13 is a perspective view of a fifth embodiment of the design taken from a point above the shaped levers.

FIG. 14 is a perspective view of the fifth embodiment of the design taken from a point below the shaped levers.

FIG. 15 is a side elevational view from the right of FIG. 13.

FIG. 16 is a front end view of FIG. 13.

FIG. 17 is side elevational view of FIG. 13 taken from the left of FIG. 13.

FIG. 18 is a rear end elevational view of FIG. 13.

FIG. 19 is a top plan view of FIG. 13.

FIG. 20 is a bottom plan view of FIG. 13.

FIG. 21 is a perspective view of a sixth embodiment of the design.

FIG. 22 is a perspective view of a seventh embodiment of the design; and,

FIG. 23 is a perspective view of an eight embodiment of the design.
